UNITED STATES PATENT OFFICE.

AXEL L. ANDERSON, OF ROCKFORD, ILLINOIS, ASSIGNOR TO PEERLESS PNEUMATIC SYSTEMS, INC., OF CHICAGO, ILLINOIS, A CORPORATION OF ILLINOIS.

SPRAY GUN

Application filed October 12, 1925. Serial No. 61,925.

This invention relates to air brushes or spray guns as they are commonly known, for atomizing and spraying with air as the transporting and motive fluid such materials as paints, fillers, enamels, varnishes, shellacs, dyes, stains and a variety of other liquid or fluid materials which it is desired to spread onto a surface for coating or finishing purposes.

10 The principal object of the invention relates to improvements in the compound spray nozzle for insuring a uniform finely divided spray under all operating conditions and positively avoiding the condition
15 of slugs and large particles of paint being discharged with the spray and ruining the character of work performed.

In the carrying out of the foregoing object I have provided a guide in the material or color nozzle for the stem of the needle valve which controls the discharge of material from the nozzle, arranged to serve to keep the valve in true concentric relation with the discharge orifice of the nozzle in all operating positions thereof.

The invention is more fully described in the following specification in which reference is made to the accompanying drawing, wherein—

30 Fig. 1 is a side view of a spray gun, a portion of the head of which is shown in section to illustrate the application of my improved needle valve stem guide;

Fig. 2 is a front view of the needle valve on an enlarged scale illustrating how it is kept centered with respect to the bore of the color nozzle, the bore being represented by a dotted circle; and

Fig. 3 is an enlarged fragmentary view of the outer end of the needle valve, a portion of which is shown in section to illustrate more clearly the construction thereof.

Spray guns of the type to which the present invention particularly relates, usually comprise a handle 4, a head portion 5, and a connecting intermediate barrel-like portion 6. The material to be discharged in an atomized condition is delivered through a neck 7 from a suitable hose connection and at a constant pressure. The transporting or motive fluid, usually air, is admitted through a hose extending from a suitable source of supply and connected at the threaded nipple 8 extending off the rear of the handle 4. A trigger 9 straddles the

body of the gun and is pivoted thereto in front of the handle 4. It is arranged to operate a needle valve 10 in front thereof to control the discharge of material from a material delivery or color nozzle 11. The trigger also has connection with the stem of an air valve 12 on a yoke 13. The yoke 13 encloses a coiled compression spring normally holding the valve 10 in closed position at the front thereof and urging the air valve 12 also forwardly to its seat within the body of the gun in the handle 4. The connections of the trigger 9 with the needle valve 10 and air valve 12 are usually such as to insure the discharging of air previous to the opening of the needle valve 10. The movement of the trigger is suitably limited by an adjustable set screw disposed behind the same and threadingly engaged in the handle 4. The discharge of air is regulated by an adjustable needle valve 15 arranged to be locked in adjusted position by a nut 16.

The details thus far described are entirely conventional and no invention is claimed therein except as they contribute in part to the carrying out of the present invention as will hereinafter appear. 80

The color nozzle 11, it will be noted, has a reduced threaded end 17 secured into the material inlet passage 18 in the head 5. It has an opposite externally threaded part 19 terminating in a conical discharge nozzle end 20. The nozzle 11 has a central bore or passage 21 which communicates at one end with the material inlet passage 18 and at the opposite end with a conical passage 22 in the nozzle end 20 terminating in a discharge orifice 23. The enlarged intermediate portion of the nozzle is suitably hexagonal in form to permit the application of a wrench in tightening the nozzle in the head 5.

wrench in tightening the nozzle in the head 5. A main air discharge nozzle 24 has a reduced cylindrical portion 25 internally threaded to screw on the externally threaded portion 19 of the nozzle 11 and has a flanged outer end 26, the periphery of which is suitably knurled for convenience in tightening the nozzle in position. The nozzle 24 has its cylindrical portion 25 providing a bearing for a flat spray nozzle 27 and the flanged end 26 jams against the end of the nozzle 27 to hold it securely in position against the flat outer face 28 of the head 5. The nozzle 27 provides an annular air chamber 29 about the nozzles 11 and 24. The air nozzle 24 has 100 105 110

a plurality, four in the present instance, of 5 equally spaced radial ports 30 connecting the chamber 29 with a chamber 31 surrounding the nozzle portion 20 and terminating in an air discharge orifice 32 concentric with the orifice 23 and surrounding the same. The flat spray nozzle 27 is shaped to provide a 10 pair of opposed heads 33 provided with passages 34 leading from the air chamber 29 in diverging relation and terminating in a pair 15 of converging discharge orifices 35 adapted for delivering two supplemental jets of air onto the atomized material discharging from the central orifice 23 for the purpose of flattening the spray into a line-like delivery. The nozzle 27 is customarily arranged to be rotated for the purpose of changing the plane of the flat spray about the axis of the compound nozzle structure, 20 that is, to produce a vertical or horizontal or any intermediate angular spray delivery. Air is conducted to the chamber 29 through a duct 36 leading rearwardly through the barrel 6 past the valve 15 to the bore of the 25 air supply nipple 8. The description thus far will suffice to show that the opening of the valve 12 produces a main discharge of air from the orifice 32 and supplemental air from the orifices 35. The material is dis- 30 charged from the central orifice 23 in regulated amounts past the pointed end 37 of the needle valve 10 shaped to fit snugly in the conical passage 22 of the nozzle 11. The character of the spray delivered 35 depends on proper atomizing, that is, proper intermixing of air with finely divided or segregated material. In previous devices considerable trouble was experienced in this particular because of the inability to main- 40 tain the nozzle in true concentric relation with the discharge orifice or, what amounts to the same thing, to the conical passage terminating in the orifice. The needle in hugging one wall in the nozzle permitted a pro- 45 portionately greater flow past the needle at the opposite wall. As a result there could be no uniformity in the spray produced and flecks and blotches were formed in the surface being coated or finished, because of 50 large slugs of the raw material being thrown onto the work without proper atomization. The difficulty referred to was found to be due to the fact that the slightest irregularities in production would throw the needle 55 out of line with the nozzle when the parts were assembled, and furthermore the needle had to be operated by connection with the stem at some distance from the nozzle and there was no way to insure proper concentricity with the nozzle at the outer unsupported end of the needle. As illustrated, the 60 stem of the needle valve 10 is reciprocable in a gland nut 38 and at this point connection is made with the trigger 9 on the cross head 39. The foregoing difficulties with re-

spect to keeping the needle in alignment with the nozzle are avoided by the provision of a spider element 40 which, as appears in Fig. 2, has three radial arms of exactly equal length arranged to center the needle valve 10 with respect to the bore 21 of the nozzle 11. Since the bore 21 is formed truly concentric with the conical passage 22 and discharge orifice 23 of the nozzle 11, the pointed end 37 of the needle valve is kept properly centered with respect to the afore-named passage and orifice. In the operation of the valve, the spider 40 slides in the bore 21 and maintains the concentric relation of the needle valve in all operation positions thereof. Due to the fact that the bore 21 is necessarily somewhat restricted, the spider 40 is preferably provided without a hub portion to fit on the stem of the needle valve 10 as this would constitute an additional restriction. Instead it has a central opening 41 through which the shank 42 of a separable needle tip 43 is arranged to fit. The reduced shank 42 fits within a bore 44 provided in the outer end of the stem of the needle valve. The shank 42 is suitably sweat-soldered, brazed or otherwise secured in the bore 44. The tip is hardened suitably by immersion in molten cyanide. A small relief vent 45 is provided at the inner end of the bore 44 to prevent the tip from being forced off in case there happens to be some moisture in the bore which would be vaporized in the heating of the tip in the hardening process. The dotted lined bore 46 may be provided, if desired, for furnishing the main atomizing air jet as disclosed in a co-pending application of Swan F. Anderson, Serial Number 721,719, filed June 23, 1924. By virtue of the guide which I have just described, the needle valve stem is always kept concentric with the central discharge orifice 23 of the material or color nozzle 11 despite any slight irregularities which may occur in the production of the nozzle itself or in the mounting of the needle valve in its guiding gland nut 38. The removability of the nozzle 11 and the nozzles 24 and 27 will not operate to destroy the alignment, inasmuch as the spider 40 will always center the needle and avoid the disalignment that sometimes occurred where the needle was sprung slightly in cleaning the gun or by coming into contact with something when the nozzles were not in place to protect the needle valve.

I claim:

1. In a spray gun having a material nozzle and an air nozzle forming a compound spray nozzle for discharging material in atomized condition, a needle valve structure for controlling the discharge from said material nozzle comprising a stem portion, a separate pointed tip portion having a reduced shank for reception in a bore provided in the end of said stem portion, and a separate spider

element arranged to be concentric with said stem and tip having a central opening to receive the shank of said tip whereby to be assembled with said stem and tip between 5 the same.

2. In a spray gun having a material nozzle and an air nozzle forming a compound spray nozzle for discharging material in atomized condition, a needle valve structure for controlling the discharge from said material nozzle comprising a stem portion, a separate pointed tip portion having a reduced shank for reception in a bore provided in the end of said stem portion, and a separate spider 10 element mounted on said valve between the stem and tip portions and held in place by the connection thereof.

3. In a spray gun having a material nozzle

and an air nozzle forming a compound spray nozzle for discharging material in atomized 20 condition, a needle valve structure for controlling the discharge from said material nozzle comprising a stem portion, a separate pointed tip portion having a reduced shank for reception in a bore provided in the end 25 of said stem portion whereby to connect the two portions together, said stem portion having a relief vent at the inner end of the bore thereof, and a separate spider element mounted on said valve between the stem and 30 tip portions and rigidly secured in place by the connection between said portions.

In witness of the foregoing I affix my signature.

AXEL L. ANDERSON.
